UNITED STATES PATENT OFFICE.

ARTHUR B. CHRISTIAN AND MARVIN S. BERRY, OF BEGGS, OKLAHOMA.

BAFFLE FOR OIL TANKS.

Application filed March 20, 1923. Serial No. 626,352.

To all whom it may concern:

Be it known that we, ARTHUR B. CHRISTIAN and MARVIN S. BERRY, citizens of the United States, residing at Beggs, in the county of Okmulgee and State of Oklahoma, have invented a new and useful Baffle for Oil Tanks, of which the following is a specification.

By way of explanation, it may be stated that sediment invariably collects in the bottom of a tank containing oil. It is necessary to draw off the sediment, subject to certain regulations, before a sale of oil can be effected. In drawing off the sediment, there is a downward draft of oil, and the consequence is that a large amount of oil is wasted.

The foregoing being understood, it may be stated that this invention aims to provide a novel form of baffle to prevent a downward suction, thereby obviating the wasting of oil during the process of extracting the sediment and foreign matter from an oil tank.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in horizontal section, a portion of an oil tank whereunto the device forming the subject matter of this application has been applied; Figure 2 is a transverse section of the structure shown in Figure 1; Figure 3 is a section taken in a plane at right angles to the cutting plane in Figure 2; Figure 4 is a fragmental horizontal section showing a modified form of the invention; Figure 5 is a vertical section showing the structure delineated in Figure 4; Figure 6 is a section taken in a plane at right angles to the cutting plane in Figure 5; Figure 7 is an elevation showing a portion of the baffle used in Figure 6; Figure 8 is a plan showing a modified form of the invention, the tank appearing in section; Figure 9 is a transverse section of the structure

shown in Figure 8; Figure 10 is a vertical sectional view showing a modified form of the invention, parts appearing in elevation; Figure 11 is a vertical section showing another modification of the invention, parts appearing in elevation; Figure 12 is a plan of the baffle used in Figure 11.

In Figures 1, 2 and 3, the numeral 1 marks a tank for the reception of oil and the like. An outlet 2 is assembled with the bottom of the tank 1 and is controlled by a valve 3. Disposed within the tank 1 and above the outlet 2 is a baffle 4, in the form of a plate. If desired, the baffle 4 may be inclined downwardly and inwardly to a slight extent, as shown in Figure 3 so as to shed any sediment which may settle thereon. The forward edge of the baffle 4 is provided with a flange 5 curved to conform to the wall of the tank 1 and fitting thereagainst. A flexible operating member 6 is assembled with the baffle 4 and extends upwardly therefrom. The numeral 7 marks a support or rod having enlarged flattened portions 8. The baffle 4 has a bearing 9 receiving the rod or support 7 and forming a hinged connection between the baffle and the rod, the bearing 9 being cut away as at 10 to clear the flattened and enlarged portions of the rod or support 7. In some or all of the parts 8 of the rod 7 are mounted adjustable legs 11, preferably in the form of bolts, nuts 12 being mounted on the bolts and the nuts engaging the bearing 8 of the rod 7, the lower ends of the bolts 90 resting on the bottom of the tank 1. Links 14 are pivoted to the ends of the support 7, the outer ends of the links being pivotally assembled with brackets 15 connected with the tank 1.

It will be obvious that since the baffle 4 is disposed above the outlet 2, there will be no direct draft of oil into the outlet 2. The consequence is, that when the valve 3 is opened, all of the sediment and foreign matter will be drawn off the bottom of the tank 1 with a minimum waste of oil, there being no appreciable down draft or flow of oil from the tank 1 into the outlet 2. The operator may swing the baffle 4 into a vertical position, at any time, by means of the operating member or chain 6, and through the instrumentality of the nuts 12, the effective length of the legs 11 may be adjusted, thereby to vary the distance between the baffle 4 and the bottom of the tank 1.

In Figures 4, 5 and 6, the tank is marked

by the numeral 16, the outlet being in the side wall of the tank, instead of in the bottom of the tank as depicted in Figure 3. The valve for the outlet is denoted by the numeral 18. Clamp members 19 hold the outlet 17 on the wall of the tank 16. The baffle is marked by the numeral 20 and has a depending flange 21 supplied with a notch 22 adapted to receive the inner end of the outlet 17, the flange 21 of the baffle being located between the inner clamp member 19 and the wall of the tank, a gasket 23 being interposed between the flange 21 and the wall of the tank. In Figure 1 the baffle 4 is approximately rectangular outline whereas, in Figure 4, the baffle 20 is of approximately semi-circular form. The foregoing will render it evident that the baffle may be of any desired shape. The vertically adjustable legs for the baffle are in the form of bolts, resting at their lower ends on the bottom of the tank and provided with nuts 25 engaging the baffle. The baffle 20 may be adjusted vertically through the instrumentality of the nuts 25, the notch 22 in the flange 21 permitting the necessary adjustment.

It will be clear that the baffle 20 will constrain the sediment and foreign matter to flow from the bottom of the tank through the outlet 17, a downward flowing of oil from the tank into the outlet 17, and a corresponding wasting of the oil being avoided.

In Figures 8 and 9, the tank is marked by the numeral 26, the outlet 27 being in the bottom of the tank. The baffle is denoted by the numeral 28 and is of circular form, the baffle being located above the outlet 27. The baffle 28 is carried by legs 29, preferably in the form of hollow standards, having nuts 30 threaded thereon, to provide for a vertical adjustment of the baffle 28. Projections or pins 31 may be mounted in the bottom of the tank 26, the projections or pins being received in the bores of the legs 29, to hold the baffle in place above the outlet 27. The form delineated in Figures 8 and 9 of the drawings will be found to be of peculiar utility in connection with wooden oil tanks.

As shown in Figures 10 and 11, the bottom of the tank appears at 50 and carries the outlet pipe 51. The baffle is marked by the numeral 52 and is of frusto-conical form, including a top 53 and an outwardly inclined side 54 from which a flange 55 extends. The supporting legs 56 are in the form of bolts, the heads 57 of which rest

on the bottom 50. The legs 56 extend through the top 53 of the baffle 52. Nuts 58 are threaded on the legs 56, and, cooperating with the top 53 of the baffle 52, afford a means whereby the baffle may be adjusted vertically. Supports 59 are interposed between the bottom 50 of the tank and the flange 55 of the baffle, the supports being held in place on the flange 55 by securing elements 60. The legs of a ladder are marked by the numeral 61 and are of tubular form, the ladder legs surrounding the upper ends of the members 56 and being supported on the uppermost nuts 58. An air pipe 62 extends downwardly through the top 53 of the baffle 52 and discharges into the outlet pipe 51, the air pipe carrying a check valve 63 preventing a back flow of liquid into the air pipe.

In Figures 11 and 12, the bottom of the tank is marked by the numeral 64 and the outlet appears at 65. The ladder legs are shown at 66 and a disk-like baffle 67 is provided, the same having outstanding ears 68 whereby the baffle is mounted slidably on the ladder legs for raising and lowering. A brace bar 69 extends across the baffle 67 and is secured thereto as shown at 70, the brace bar being provided at its ends with means 71, such as chains, whereby the baffle may be raised and lowered.

What is claimed is:—

1. In a device of the class described, a tank having an outlet; a substantially horizontal baffle in the tank and located above the outlet, the baffle extending laterally beyond the periphery of the outlet; and means for raising and lowering the baffle with respect to the outlet.

2. In a device of the class described; a tank having an outlet; a baffle in the tank and located above the outlet; means for adjusting the baffle vertically with respect to the outlet; and means for swinging the baffle toward and away from the outlet.

3. A device of the class described comprising a tank having an outlet; a baffle disposed above the outlet; and means for supporting the baffle, said means including legs engaging the bottom of the tank, and means carried by the legs for engaging the baffle to effect a vertical adjustment of the baffle.

In testimony that we claim the foregoing as our own, we have hereto affixed our signatures.

ARTHUR B. CHRISTIAN.
MARVIN S. BERRY.
